UNITED STATES PATENT OFFICE.

EUGENE W. VEST, OF ST. LOUIS, MISSOURI.

GAS-BURNING SYSTEM FOR FURNACES, HEATING-STOVES, RANGES, &c.

1,325,492.

Specification of Letters Patent. Patented Dec. 16, 1919.

Application filed April 8, 1918. Serial No. 227,245.

To all whom it may concern:

Be it known that I, EUGENE W. VEST, a citizen of the United States, residing at St. Louis, in the State of Missouri, have invented certain new and useful Improvements in Gas-Burning Systems for Furnaces, Heating-Stoves, Ranges, &c., of which the following is a specification containing a full, clear, and exact description, reference being had to the accompanying drawings, forming a part hereof.

My invention relates to an improved gas-burning system for furnaces, heating-stoves, ranges, hot-water heaters, and other heating apparatus of whatever nature; and it consists in the novel disclosure hereinafter fully described, and particularly pointed out in the claims found at the end of this specification.

20 The object of my invention is to provide an improved gas-burning system which may be readily and economically applied to furnaces, heating-stoves, ranges, hot-water heaters, portable small room heaters, &c., now in use burning coal or other fuel, as well as to new ones which may be hereafter manufactured; whereby such devices will be converted into gas-burning apparatus in the most economical manner, and which 25 will thereafter produce the maximum of heat with the expenditure of a minimum quantity of gas.

A further object of my invention is to provide means which shall direct the hot 30 expanded gases to the top of the furnace, stove, range, or heater, and thereat retard them against too rapid exit into the usual additional expansion chambers, where radiation continues to absorb heat and radiate 35 same; and this object is accomplished in the most scientific manner by regulating the area of the exit opening (or passage) in accordance with the well known formula of Prof. Pole for the flow of gases in pipes 40 heated to any degree above 60° Fahrenheit, viz: $1/520$ for every degree above 60 degrees, so that the said exit passage will be so restricted at all times as to permit very little heat to escape, and yet permit sufficient draft 45 for perfect combustion, as well as to carry off the products of combustion.

My invention further consists in certain details of construction and arrangement of parts, as will be hereinafter more fully described in connection with the drawings, in 55 which—

Figure 1 is a vertical section of a furnace having my invention applied thereto, the section being taken approximately on the line 1—1 of Fig. 2.

60 Fig. 2 is a horizontal section of the same, taken approximately on the line 2—2 of Fig. 1.

Fig. 3 is a view looking down upon the upper portion of the fire-chamber of the 65 furnace, as indicated by arrows of the line 3—3 of Fig. 1, the top of the fire-chamber being removed.

Fig. 4 is a detail view of the united inner 70 ends of the exit-tubes, and their valved-inlet end, as arranged to direct the hot expanded gases to the central top of the fire-chamber, and to retard said gases thereat for economical reasons, as well as for greater efficiency.

Fig. 5 is a detail elevation of the edges 75 of the superposed fire-clay slabs having peripheral baffles arranged in "staggered" relation, to intercept the rising heated gases as they are discharged by the burners beneath them.

Fig. 6 is a perspective view of one of the base-segments of the burner construction.

Fig. 7 is a detail vertical section of a portion of a lighter-tube, with a lighting jet or tip applied thereto.

Fig. 8 is a sectional side-elevation of one form of my gas-valve and air-valve connections, as applied to the outer casing of a furnace or stove.

Fig. 9 is a front elevation of the gas-valve 90 cam connected to the air-valve, and looking in the direction indicated by the arrows of Fig. 8, said arrows being designated by the numerals 9—9.

Fig. 10 is a cross-section through the air-valve, taken on line 10—10 of Fig. 9.

Fig. 11 is a vertical section of a portion 95 of the outer casing of a furnace or stove, having one form of my burner-construction applied thereto.

Fig. 12 is a sectional plan-view of the top-segments of the burner covering, illustrat-

ing the "staggered" relation of said segments and the underlying base-segments of refractory material, the body of fire-clay "biscuits" being removed from said top-segments.

Fig. 13 is a sectional side-elevation of a stove having my invention applied thereto in a slightly modified form.

Fig. 14 is a section through the body of said stove, on the horizontal line 14—14 of Fig. 13.

Fig. 15 is a diagrammatic plan-view of the modified arrangement of the burners in a "straight line," to adapt them for use in 15 the fire-box of a range.

Fig. 16 is a view of a portion of the lighter-tube, having a series of lighter-jets applied thereto, and illustrating the function of successive lighting of all the jets 20 upon the lighting of an initial jet.

Fig. 17 shows a modification of my invention, as applied to a light portable bath-room heater, and which can be used as a heater for other purposes, and for cooking; and

Fig. 18 is a horizontal section through said room-heater, taken on the line 18—18 of Fig. 17.

The numeral 1 designates the outer wall of the furnace, stove, or heater; there being an 30 outer casing 2 inclosing all the heating members of the apparatus in cases where my invention is applied to heating-furnaces and the like. (See Figs. 1 and 2.)

The said outer casing 2 of the furnace is 35 provided with the usual fire-doors 3, ash-pit opening 4, and hot-air pipe-connections 5, all as found in the furnaces now in use.

The fire-box is greatly reduced in size by placing against the inner surface of the said 40 wall 1 a circular lining 6 of fire-clay or other refractory material, which extends completely around said fire-box, as shown in Fig. 12, and reduces the diameter of the fire-box considerably; but the diameter of same 45 is still further reduced by a core 7 of highly refractory material, such as fire-brick or blocks, located centrally of said fire-box and supported upon a suitable foundation, which, in the present case is a cast-iron pedestal 8, which stands in the ash-pit 9, with 50 its lower end resting upon a suitable base or foundation 10, or it may be directly supported by the earth or floor of the room or basement in which the furnace is located.

Said refractory lining 6 may be supported by angle-bars 11, fastened to and projecting from the inner surface of said wall 1. See Figs. 1 and 11.

Said core 7 is made conical at its upper 60 end, and made to overhang the burners (hereinafter described), as well as to still further reduce the size of the fire-chamber or fire-box, by carrying upon its upper end a series of superimposed layers of fire-clay

12, the outer peripheries of which are inclined in such a manner that said series of layers form an inverted cone-shaped body of refractory material increasing in size or radius toward its upper end, and greatly reducing the size of the space in the fire-chamber between the inclined outer edges of said layers and the said wall 1 of the furnace or stove, and (in operation) forcing the heated air outwardly against the wall of the fire-chamber.

To still further increase the efficiency, I place upon the said cone-shaped body of refractory material, (the layers 12) a series of superimposed fire-clay slabs 13, which are semicircular in plan-view, as shown in Fig. 3, and have integral peripheral baffles 14 arranged in "staggered" relation, as shown in Fig. 5, and against which baffles the rising heated gases impinge, and are thereby caused to part with an additional portion of heat, which is absorbed by the closely adjacent wall 1 of the furnace or stove.

Although I have shown the said slabs 13 and the layers 14 in the form of semicircular disks, it is to be understood that I do not limit their shape to the form in which they are here shown, it being obvious that they may be made in any other form which will reduce their size sufficiently to enable them to be readily placed in position in the furnace or stove.

Such a construction of a baffling-core, it will be seen, fills a great part of the fire-chamber, and extends the said baffles so far upwardly that they are located near to the point in said chamber at which the expanded gases make their exit.

To cause the expanded gases to rise still higher in the fire-chamber and be brought into direct contact with the top 15 thereof, and to retard said gases therat under such circumstances as economy dictates, I provide a damper 16 to control the exit opening; and in the present illustration of my invention such damper is pivotally mounted upon the common journals across the opening of the united inner ends of two exit-tubes 17, 17, which extend radially from the central portion of said fire-chamber (at a point close to said top 15) to and through the wall 1, and have their outer ends connected to the usual vertical radiating-chambers 18, the lower ends of which latter are connected to the common radiating-chamber 19, having the usual smoke-pipe or chimney-pipe 20.

The inner ends of the said exit tubes 17, 17, are supported by a suitable horizontal rod or bar 21 extending across said fire-chamber and having its opposite ends fixed to the walls of said chamber, in any desired workmanlike manner.

The said exit opening, controlled by the said damper 16, is so restricted at all times

(even when the said damper is wide open) as to permit very little heat to escape, and yet such restriction is not sufficient to interfere with the passage of sufficient draft for perfect combustion of the gas.

- 5 One form of burner and connecting means for accomplishing the above results is herein shown and described; but the preferred form of burner and gas-valve form the subject-matter of two companion applications 10 for patents, of like date of filing, which is the date of filing the present application; one of said companion applications being entitled "Gas-burner for furnaces, heating- 15 stoves, ranges, and the like," Serial No. 227,244, while the other companion case is entitled "Valve for the gas burners of furnaces, stoves and ranges," Serial No. 227,246.
- 20 The connections for controlling the above-described damper 16 will be described in detail later on herein, when I reach the detailed description of the burner and gas-valve.
- 25 *The burners, gas-valves, and their connections.*

Any desired number of burners may be installed in a furnace, stove, range, or 30 heater, depending upon the service to be performed, and in the furnace shown in Figs. 1 and 2 there are four pairs of burners, or eight burners in that furnace; while in the stove shown in Fig. 13 there is a 35 smaller number of burners, and in the portable heater of Fig. 16 there is but one burner shown.

The vertical secondary-air pipe 22 surrounds the vertical discharge-pipe 23 of the 40 primary-air and gas mixture, both pipes being united in a single casting, as shown more clearly in Fig. 11, and the upper end of said secondary-air pipe projects through an aperture 24 formed in its individual base- 45 segment 25 of the burner construction, so that the mixture of gas and air from said discharge-pipe 23, as well as the secondary air from the said pipe 22, will be discharged upwardly into the lower portion of the fire- 50 box, and impinge upon the undersides of the refractory top-segments 26 of the burner-covering, which overlie said discharge pipes, and are spaced apart from same, and are supported by bricks or blocks 27 of fire-clay 55 or other suitable refractory material placed under the opposite ends of said top-segments, and themselves spaced apart to form beneath said top-segments a combustion space 28, whence the fire passes around the 60 said bricks or blocks and around the said top-segments through suitable passages 29 between the edges of adjacent ones of the said top-segments 26, and up against and through the interstices of a layer or body of

fire-clay "biscuits" 30 of well known form 65 (or through a body of similar highly refractory material which is in small pieces, after which the rising hot gases strike against the overhanging parts of the previously described "spreader" cone of refractory material, to-wit: the conical layers 12 and the "staggered" baffles 14 of the said layers 13, whereby the combustion is completed and the heat is applied in the most efficient manner, as previously described. 70

The vertical discharge-pipes 22 and 23 are, as before stated, united as a casting, which is supported by a suitable means, which is (in the present case) in the form of a pedestal 31 the upper end of which is 80 threaded into said casting while its lower end is provided with a suitable base-casting 32 resting upon the floor or base of the furnace or stove, said floor having been previously designated by the numeral 10. 85

The said burner castings are preferably united as pairs, two sets of the said discharge-pipes 22 and 23 being united by lateral extensions 33 and 34, respectively, both of which are hollow. 90

The extension 33 has the inner end of its mixing-pipe 35 threaded into it, to supply a suitable gas-and-air mixture simultaneously to each discharge-pipe 23 of the pair, while the other lateral extension 34 is in the 95 form of a hollow forked dirt-receptacle, the inner ends of the forks of which are in communication with the interior of the said gas discharge-pipes 23 of the pair, while the united outer ends of said forks have the inner ends of clean-out pipe 36 threaded into them, the said clean-out pipe being extended to a point adjacent the outer casing 2 and provided thereat with a common detachable cap 37 accessible by way of a clean-out hole 100 38 cut in said outer casing and normally closed by a removable cover or slide 39, for an obvious purpose.

Where the said clean-out pipes 36 pass through the wall of the ash-pit (or lower 110 part of the stove or furnace) a tight joint is maintained thereat, to prevent air from the interior of the outer casing 2 from entering the ash-pit, by nipples 40 threaded into the apertures through which said clean-out pipes pass, and locked securely in position by means of lock-nuts 41. (See Fig. 11.)

The outer end of each of the said mixing-pipes 35 is connected to a detachable gas-valve casting having an air-throat 42, the 120 connection being made by means of a threaded coupling 43 into which the threaded ends of the mixing-pipe and its gas-valve casting are screwed and abut, the said gas-valve casting being, of course, located upon the exterior of the furnace or stove, for convenience of manipulation during use. (See Fig. 8.) 125

An important feature of my gas-valve construction is the detachable (and therefore interchangeable) tip 44 the outer end of which is removably secured by screw-threads 5 to the inner portion of the horizontal gas-throat 45 of the said gas-valve casting, whereby the gas man or other attendant may readily put on whatever size of tip he may think is most desirable for the service required; and also important is the further feature (shown in Fig. 8) of making the discharge-orifice 46 of the said tip so large that it cannot be completely closed by the end 47 of the gas-valve stem which co-operates with it, whereby the gas-valve can be turned down but cannot be turned completely off, thus enabling the burner to operate when turned down to the limit upon a very small quantity of gas, without the trouble of relighting it every time it has been turned down.

The numeral 48 designates the gas supply pipe, which is arranged to supply all of the gas-valves of the series, the said gas-throat 25 45 of each gas-valve casting being connected detachably to the said supply-pipe by means of a common union 49 and shut-off cock 50, for obvious purposes.

A very quick opening and closing of the 30 gas-valve is obtained by means of a worm 51 on the gas-valve stem engaging corresponding threads upon the interior of a worm-bore formed in the stuffing-box member 52 of the gas-valve casting, a metallic 35 washer 53 being located on the free end of said member, to receive the thrust of the stuffing-box gland 54 upon the packing 55.

Simultaneous regulation of both the entrance of the air to the air-throat 42 of the 40 said gas-valve casting, and the supply of gas passing through the discharge-orifice 46 into said mixing-pipe 35, is secured by a slide-valve 56 having its opposite edges mounted to move in dovetailed guides 57 45 across the entrance to said air-throat, and a suitable connection between said gas-valve stem, which will cause said slide-valve and said stem to move in unison; whereby the turning up or down of the gas will simultaneously regulate the air, to produce the 50 Bunsen flame required for the most efficient and economical operation.

In the present illustration of this part of my invention I have provided a cam 58, 55 which is fixed upon the gas-valve stem at a point between the said stuffing-box gland 54 and the stem handle 59, the projecting lip 60 of said cam being embraced by a U-shaped bearing at the lower end of a vertical shank 60 61 on the lower edge of said slide-valve; whereby when said gas-valve stem is rocked or rotated the said cam will cause a corresponding movement of said slide-valve, and more or less close or open the entrance to the 65 said air-throat 42, the said slide-valve hav-

ing (in the present instance) an opening or perforation 62 which registers with the entrance to the said air-throat when the said valve is moved to a position to uncover said entrance.

The said U-shaped bearing at the lower end of said valve shank 61 is designated by the numeral 63.

Furthermore, a simultaneous regulation of all of the gas-valves of a series, as well as 75 the simultaneous regulation of all the slide-valves of the same series that may be applied to a furnace, as shown in Figs. 1 and 2, is readily obtained by pivotally connecting a coupling-rod 64 to each gas-valve handle 59 80 by means of a suitable pivot 65, which will cause all of said parts to move in unison, and thereupon regulate the action of all burners that are so connected, by the movement of but one of the said gas-valve handles, if so desired.

Suitable movable stops 66 are secured to the said lip 60 of said cam 58 by means of common screws or some similar fastening device, to come into contact with the said U-shaped bearing 63 (or some common fixed object) when said cam is rotated or moved, and thereby limit the extreme movement of said cam in either direction, so that a greater or less quantity of gas can be used when the 95 gas is turned on or turned down to the desired limit, and thereby form a "measure" for the least and greatest quantity of gas and air to be used.

Furthermore, a simultaneous regulation of 100 all the gas and air valves of the burner (or of one gas-valve and one air-valve of a burner) and the exit-damper 16 in the top of the fire-chamber of the furnace, stove, or range, (to prevent a too rapid exit of the hot 105 expanded gases at all times, no matter what the position of the gas-valve and the air-valve) may be produced by suitable connections with the said exit-damper and said gas and air valves, no matter whether the valves 110 be moved by hand or by one of the well known thermostatic damper regulators now on the market.

One form of such an arrangement is herein shown at Fig. 1, while a slightly modified form of the same arrangement is shown in Fig. 13, both of which views exhibit a suitable rod or other connection 67 pivotally secured at 68 to the upper part of the air-valve 56, and extending up to the bell-crank 120 69 pivotally mounted at 70 upon a bracket 71 fixed to the front of the furnace or stove, and connected to the crank 72 of the said exit-damper by a horizontal rod 73.

Furthermore, in such cases as require still 125 further economy and close regulation, the common damper 74 in the smoke-pipe 20 has its crank 75 connected to a short vertical rod 76, the upper end of which latter is pivoted at 77 to a crank 78 fixed upon the additional 130

horizontal rod 79 extending across the top of the furnace casing 2 and mounted in suitable bearings 80 therein, and carrying another crank 81 on its front end pivoted at 5 82 to the extended upper end of the said rod 67; whereby the smoke-pipe damper, the exit-damper in the top of the fire-chamber, the air-valve (or valves) and the gas-valve, will all be moved simultaneously, and accomplish the objects before recited.

10 A common reticulated cone, made of wire cloth or other suitable material, as designated by the numeral 83, is fixed in the said air-throat 42 of the gas-valve casting, to act as a strainer, and to prevent "back firing," in the usual or well known manner. (See Fig. 8.)

Common lighter-tubes 84 are provided with the usual lighter-tips 85, and are connected to the service or gas-supply pipe 48, for lighting the burners in the usual manner, some of the said tips 85 having a lateral tip 86 for communicating the flame to the next adjacent lighter-tip of the series, 20 as shown in Fig. 15, each of said lighter-tubes being provided with a common cock 87 near the said service pipe, for turning on and shutting off the gas for said lighting devices.

30 *As to the modifications herein noted.*

I do not desire to limit myself to apparatus which use only the fuel commonly known as "gas," but I may use any form 35 of fuel, whether it be generated in a special gas-works and then be carried to the place of consumption in pipes, as the gas commonly done, or whether it be generated in the fire-box of the furnace, stove, or range; 40 and therefore some portions of my invention, especially the spreader-core 7 and its parts which overhang the burners, may be readily used in coal-burning furnaces, stoves, ranges, and heaters, and be supplied 45 with super-heated air in any known way, for the purpose of assisting in the combustion of the smoke and combustible gases, inasmuch as it is clear that such parts will 50 perform their several functions in substantially the same way, no matter what fuel is used in the apparatus.

Similarly, in localities where there is no gas-works and no natural gas conveniently available, the burners shown herein may be 55 supplanted by any suitable known form of oil-burner or burners, and the remaining devices will perform their several functions in substantially the way they perform them when gas-works or natural gas is used.

60 Referring to the stove modification, shown in Fig. 13, it will be seen that my invention may be applied to any common heating-stove now in use burning coal, and such is the general form of the stove there 65 shown, the construction and operation of

the substantial parts of my invention being substantially the same in said stove as they are in the furnace herein shown.

Referring to the modification of the arrangement of the burners in a range fire-box, shown diagrammatically in Fig. 15, it will be understood that the burners are located in a "straight-line" with respect to each other, in order that they may occupy a long and comparatively narrow rectangular fire-box.

Referring to the portable heater shown in Figs. 17 and 18, it will be observed that the heater is provided with a common top or cover 88, which may be readily detached to permit cooking utensils being placed in position for action by the fire, the body of fire-clay "biscuits" 30 being extended to or near the upper end of the heater, and said biscuits resting upon a disk of refractory material 89 having its marginal edge provided with a series of fingers 90 between which the fire from the burners (or it may be a single burner) passes upwardly into and through the said biscuits.

The outer casing 1 of said heater being lined by a body of refractory material 6, which extends the full height of said casing in the present illustration.

The underside of the said disk 89 is preferably formed in the shape of an inverted cone, for the obvious purpose of "spreading" the flames from the center outwardly toward the openings between said fingers 90.

The outer ends of said fingers 90 rest 100 upon the suitable fire-clay or other refractory supports 27, which in turn rest upon the base 25 having a central aperture 24 through which the discharge-pipes 22 and 23 of the burner projects.

105 The heater is provided with the usual bail or handle 91, for convenience in carrying the heater from place to place.

The remaining parts of the heater need not be described, as their construction and 110 use will be readily apparent when taken in connection with the description of the parts of the furnace and stove, previously given.

I do not limit myself to a spreader core 7 that is cylindrical, nor to the parts which 115 overhang the burner (or fire-bed) in circular form, as it is obvious that said core and said overhanging parts may be elongated in a horizontal plane, so as to fit a long and narrow fire-box or fire-chamber, or to fit 120 a square or oblong one, in contradistinction to circular fire-boxes, the only essential being that said core and said overhanging parts retain the substantial T-shape in cross-section, no matter what sort of a fire-box 125 they are located in the center of.

As shown in several views, the said lower portion of said core 7, as well as its pedestal or supporting device 8, are hollow or tubular; and as illustrated in Fig. 13 there is 130

an air-entrance opening 92 formed in the base of said pedestal and registering with an opening formed in the base of the ash-box or ash-pit, whereby cold air may enter 5 said openings and pass upward through said pedestal and said hollow core 7 to a central opening 93 formed in the said layers 12 and 13 of the fire-clay slabs composing the overhanging portions of the spreader core, 10 and from said central opening the air will pass (after being super-heated by the hot parts through which it passes) outwardly through radial channels 94 formed in said layers, and commingle with the hot gases 15 for the more perfect combustion of the fuel.

The operation of my invention is simple, and will be clear to those skilled in the art, by reading the above description.

I claim the following as my invention:

1. In a furnace or heating - stove, a "spreader" core located in the fire-chamber thereof and composed of a refractory lower portion, which has vertical sides; a conical portion above said lower vertical portion; 5 and a series of slabs of refractory material superimposed above said conical portion and having at their edges staggered baffles against which the rising heated gases impinge.

2. A refractory core for the fire-chambers of furnaces, stoves and heaters, composed of a hollow lower portion, a suitable support therefor, means whereby air may enter said lower portion, superposed layers of slabs of refractory material placed upon the upper end of said lower portion and having air-passages communicating with the interior of said hollow lower portion and extending to the peripheries of said slabs, whereby the super-heated air will be discharged into the fire at said peripheries, and staggered baffles projecting from the peripheries of some of the said slabs, the slabs which carry said baffles being of sufficient horizontal dimensions to overhang the burners or fire-grates of the apparatus in which said refractory core is to be used.

3. In a stove or furnace, the combination of a series of burner base segments arranged in a circle, each of said segments having an

aperture through which the air and gas from a burner may pass; a series of burner top-segments made of highly refractory material and arranged in a circle with a space between their adjacent edges; and blocks of 55 refractory material which space said top-segments from said base-segments and act as a support for said top-segments, said blocks being themselves spaced apart to form beneath said top-segments a combustion space, 60 whence the fire will pass around said blocks and up through said spaces between the edges of said top-segments.

4. In a furnace or stove, the combination of a series of burner top-segments made of 65 refractory material and arranged in a circle with their edges separated to form a space between adjacent segments; a core of refractory material at the center of said circle of top-segments; and a body of fire-clay "biscuits" or the like supported by the said top-segments and arranged around said core.

5. In a furnace or stove, the combination of a series of burner base-segments arranged in a circle and having an aperture; and a 75 series of burners arranged in a circle with their discharge-pipes in position to discharge air and gas through the apertures of said base-segments.

6. In a gas-burner for furnaces and 80 stoves, a plurality of burner castings having vertical pipes for the air and gas arranged concentrically for each burner, and said plurality of castings being united by hollow extensions which form respectively the mixing-pipe connections and the hollow forked dirt-receptacles; mixing-pipes connected to said mixing-pipe connections; and clean-out pipes connected to the united outer ends of 85 said dirt-receptacles and extended to a point 90 adjacent the outer casing of the stove or furnace and thereat provided with common detachable caps.

In testimony whereof I have signed my name to this specification in presence of two 95 subscribing witnesses.

EUGENE W. VEST.
